MICHAEL OROS, OF SEATTLE, WASHINGTON.

LAMP-BURNER.

1,254,623.

Specification of Letters Patent. Patented Jan. 22, 1918.

Application filed September 30, 1916. Serial No. 123,179.

To all whom it may concern:

Be it known that I, MICHAEL OROS, a citizen of the United States, residing at Seattle, in the county of King and State of Washington, have invented a new and useful Improvement in Lamp-Burners, of which the following is a specification.

This invention relates to improvements in lamp burners, and the object of this improvement is to provide a cheap and simple burner for a signal lamp or lantern that will prevent the leakage of oil when the lamp is turned into inclined or inverted positions.

The invention consists in the novel construction of a lamp burner and in the adaptation and combination of parts, as will be more clearly hereinafter described and claimed.

In certain kinds of work, particularly in railroading, a great deal of signaling is done with signal lamps, and this signaling necessitates the lamp being frequently turned into inclined or inverted positions, thus causing the oil to tend to flow outwardly through the burner and run down over the sides of the lamp. The same condition is often present where the lamp is carried upon the arm of the user, as is done in certain kinds of work in railroad yards and similar places.

In the construction of lamp burners it is customary to leave a vent hole therein which communicates either directly or indirectly with the oil cup of the lamp to admit air and equalize the pressure within the oil cup as the oil is removed therefrom; and in the burners now in common use on signal lamps, when the lamp is turned into an inclined or inverted position, the oil in the oil cup oozes out through this vent hole and around the wick, and runs down over the sides of the lamp, thus not only wasting oil but greasing and soiling the clothes of the workmen, the floors on which the lamp is set, and everything else with which the lamp comes in contact.

This burner is designed to prevent the leakage of oil in the manner above described, thus effecting a saving in the amount of oil consumed and a greater saving in the clothing of workmen who are obliged to use signal lamps.

In the drawings, Figure 1 is a view in side elevation of a burner constructed in accordance with this invention, showing an oil cup in cross section; Fig. 2 is a view in vertical

section on broken line 2, 2 of Fig. 1; Fig. 3 is a plan view of the burner; Fig. 4 is a view in cross section on broken line 4, 4 of Fig. 2; Fig. 5 is a view in cross section illustrating the burner as it may appear when the lamp is turned into an inclined position; Fig. 6 is a fragmentary cross sectional view of the burner as it may appear when the lamp is inverted; and Fig. 7 is a fragmentary view in cross section, illustrating a slightly modified form of the device.

Referring to the drawings throughout which like reference numerals indicate like parts, the numeral 10 indicates a cylindrical casing that incloses a chamber, 11, and forms the base portion of my burner, the lower end of such casing preferably being exteriorly threaded, as at 12, to adapt it to be screwed into the neck of an oil cup, 13, as shown in Figs. 1 and 5.

14 is another casing disposed above the casing 10 and secured thereto to form an overflow chamber, 15, for oil, the top of the casing 14 preferably having a convex central portion, 16, a depressed annular trough-like portion, 17, and raised edges, 18, for purposes hereinafter explained.

20 is a wick guide that extends upwardly through the casing 10, and terminates within the overflow oil chamber 15; and 21 is another wick guide that extends downwardly through the top of the casing 14 and terminates within the chamber 15 at a point slightly above the top of the wick guide 20. The bottom end of the wick guide 21 is preferably flared slightly, as indicated at 22, to facilitate the insertion of a wick, 23, although this feature is not essential.

24 are spur wheels that are mounted on a spindle, 25, and project through slots, 26, in the sides of the wick guide 20 in a well known manner so that they will engage with the wick and move it up or down within the wick guides. The spindle, 25, projects outwardly through the side of the casing 10, and is provided with a finger wheel, 27, by which it may be turned.

The top wall of the casing 10 is provided with a vent hole, 28, which communicates with the overflow chamber, 15, and the top wall of the casing 14 is provided with a vent hole, 30, that is located within the bottom of the annular depression, 17, and forms a passage between the chamber 15 and the atmosphere.

In Fig. 7 the wick guide 21 is shown to terminate flush with the inside surface of the top wall of the casing 14, and the wick guide 20 to project upwardly within the chamber 15 to a point near the bottom of the wick guide 21.

Manifestly, this is substantially equivalent to the form shown in Figs. 1 to 6, the essential feature as hereinafter pointed out being 10 the break or space between the wick guides at some point within the chamber 15, to permit excess oil to ooze out into the chamber 15 when the lamp is moved into an inclined or inverted position.

15 The casing 10, having the vent hold 28, wick guide 20, and moving apparatus as shown, are old and well known features, and when taken alone are substantially identical with a type of burner in use at the 20 present time. This invention resides in the provision of the auxiliary casing 14 and wick guide 21, whereby the overflow oil reservoir 15 is formed.

In the use of a burner of the ordinary type 25 without the overflow oil chamber, 15, and auxiliary wick guide, 21, when the lamp is inclined or inverted the oil, indicated by "O," will create a pressure back of the burner and will flow upwardly through the 30 wick guide and out of the top thereof faster than it can be consumed by the flame when the lamp is lighted. In addition to flowing out around the top of the wick guide, oil will also ooze out through the holes, 26, into the 35 chamber 11, and will flow from there out through the hole 28, and run down over the sides of the lamp.

In the use of my burner, when the lamp is inclined or inverted (see Figs. 5 and 6) excess oil that flows from the top of the wick 40 guide 20 will drip off into the overflow oil chamber 15 in the manner indicated at 31 in Fig. 5; and excess oil that finds its way into the chamber 11 and flows outwardly through hole 28 will be caught in the chamber 15, thus preventing it from getting outside of the burner.

The hole 30 is located in the annular trough-like portion 17 of the casing 14, so 50 that the small amount of oil that will ordinarily find its way into the chamber 15 at any one time will not be sufficient to submerge such hole, 30, and flow outwardly therethrough. Moreover, if sufficient oil 55 does collect in the chamber 15 to submerge the hole 30, the pressure within the chamber will be so slight that oil will run out very slowly.

As soon as the lamp is turned into an up- 60 right position, the oil in the chamber 15 will flow through the hole 28 into the chamber 11, and from there will flow through openings 26 into the oil cup 13, or will be taken up by the wick, 23.

65 The distance or space between the lower

end of the top wick guide, 21, and the top end of the bottom wick guide, 20, may be varied without effecting the operation of the lamp, the essential feature being that a space be left between such two ends within 70 the chamber 15 so that excess oil may drip out into the chamber 15 instead of flowing from the top of the wick guide, 21, faster than it can be consumed.

If desired, the spur wheels, 24, and balance of the wick-moving mechanism may be placed within the casing 14 instead of within the casing 10.

The lamp or lantern frame for the reception of the bowl 13 forms no part of the invention and is not herein shown or described.

Obviously changes in the form of construction and arrangement of parts of this invention may be made within the scope of the following claims.

What I claim and desire to protect by Letters Patent is:—

1. A lamp burner comprising a plurality of compartments disposed one above another and having communication with each other 90 through small openings, the top portion of the uppermost compartment having small vent holes and the lowermost compartment having communication through a restricted opening with the oil cup of a lamp, and a 95 two part wick guide extending upwardly through said compartments, the two parts of said wick guide being spaced apart to afford an opening between the ends thereof within one of said compartments whereby excess oil may drain off through said opening. 100

2. A lamp burner comprising a body portion having a lower and an upper compartment, said compartments having communication with each other by means of small 105 vent holes said lower compartment having communication through a small opening with an oil well and said upper compartment having vent holes in the top wall thereof, a two part wick guide extending 110 through said compartments, the two parts of said wick guide being spaced apart to permit excess oil to escape within one of said compartments.

3. A lamp burner comprising a body portion having two separate compartments, a wick guide projecting upwardly through the lowermost of said compartments and terminating in the uppermost of said compartments, wick moving means in said lowermost 115 compartment, and a wick guide projecting downwardly into said uppermost compartment in alignment with said first named wick guide and having its lower end spaced from the upper end of said first named wick guide. 120

4. A lamp burner comprising a body portion having an upper and a lower compartment divided by a partition wall said partition wall having a vent hole therethrough, a two part wick guide extending upwardly 125

130

through said compartments the two parts of said wick guide being spaced apart to leave an opening between the two ends thereof within said upper compartment, and a 5 vent hole in the top wall of said upper compartment.

5. A lamp burner comprising a body portion having an upper and a lower compartment divided by a partition wall, a vent hole 10 in the top wall of said upper compartment, another vent hole in said partition wall, a wick guide projecting upwardly through said lower compartment and terminating in said upper compartment, said wick guide 15 having slotted holes therein, spur wheels to project through said slotted holes and engage a wick, means for turning said wheels, and a wick guide projecting downwardly through the top wall of said upper compartment 20 in end to end alinement with said first named wick guide and terminating at a dis-

tance therefrom to leave a space therebetween.

6. A lamp burner comprising a body portion having an upper and a lower compartment divided by a partition wall said partition wall having vent holes through which liquid may pass downwardly, a two part 25 wick guide extending upwardly through said compartments the two parts of said 30 wick guide being spaced apart to leave an opening between the two ends thereof within said upper compartment through which excess oil may escape.

In testimony whereof I affix my name in 35 the presence of two witnesses this 25th day of September, 1916.

MICHAEL OROS.
